PUSHER MACHINE AND COKE GUIDE
INTERLOCK

John W. Drake, Leetsdale, Pa., assignor to Koppers Company, Inc., a corporation of Delaware

Application January 11, 1947, Serial No. 721,620
In Great Britain January 16, 1946

14 Claims. (Cl. 214—23)

1

This invention concerns improvements in or relating to coke discharging plant for the ovens of horizontal coke oven batteries, and particularly to plant of the kind which comprises a pusher machine adapted to travel intermittently along one side (hereinafter called the "pusher side") of a coke oven battery and carrying a pusher ram, and means for pushing this ram into and through the ovens of the battery, one at a time, to discharge the coke from the ovens at the side (hereinafter called the "coke side") of the battery opposite to that along which the pusher machine is adapted to travel, the coke so discharged being directed by a coke guide forming part of the coke guide machine into a quenching car which, like the coke guide machine, is adapted to be traversed along the coke side of the battery, the pusher machine and the coke guide machine being provided or associated with door operating means for removing the oven doors respectively at the pusher side and the coke side of the oven battery to enable the ovens to be discharged.

It is usual for the ram of the pusher machine to be driven forwardly into the oven on its pushing stroke by electrically operated means and to be withdrawn from the oven by the same means, an electrical control box being provided in the control cabin of the machine for regulating the operation of the pusher ram.

In the past, there had been a liability for accidents to occur from which damage to the battery structure or injury to the operators could result, these accidents being due to the operator at the pusher side of the battery bringing the pusher machine opposite to and removing the pusher side door of an oven different from that with which the operator in charge of the coke guide machine has aligned that machine and from which oven he has removed the door at the coke side of the battery, with the result that when the pusher ram is driven into the oven with which it is aligned, the unopened door at the coke end of this particular oven takes the full force of the powerful ram and is either broken or pushed off the door frame and/or the oven structure surrounding the door frame is badly damaged and the adjacent buckstays distorted. In addition there is, in these circumstances, always the danger of injury to the operator at the coke side of the batteries occurring.

Various systems for providing an interlock between the pusher machine and the coke guide machine of an oven battery have been proposed hitherto for the purpose of eliminating the above-mentioned liability of accidents occurring, and

it is an object of this invention to provide an improved interlocking system of this general character and whereby improved pusher control is achieved.

5 According to the present invention, there is provided a coke-oven discharging plant of the kind referred to, wherein are provided pusher ram control means for normally rendering the pusher ram inoperable in a forward direction; a pipe line for and adjacent each oven of the battery, such pipe lines extending from the pusher side to the coke side of the battery; a pressure fluid supply source carried by and travelling with the pusher machine or the coke guide machine; coupling means for temporarily coupling the said pressure fluid supply source to one of the said pipe lines at a time and being such that the coupling of the supply source to a pipe line can only be effected when the machine carrying the said supply source is aligned with the oven with which the pipe line to be coupled is associated; and fluid pressure operated means adapted to be actuated by fluid pressure built up in a pipe line connected to the said supply source 10 and adapted to operate the said pusher ram control means, to render the ram operable in a forward direction, only when the pusher machine and the coke guide machines are aligned respectively with the opposite ends of the same oven.

15 20 25 30 35 40

In accordance with a further aspect of the invention, there is provided a coke-discharging plant of the kind referred to, including electric switch means normally rendering inoperative the electric driving gear for effecting the forward or pushing stroke of the pusher machine ram, and fluid pressure operated means—energized from a pressure fluid supply source carried by and travelling with the pusher machine or the coke guide machine—adapted to operate the said electric switch to enable the pusher ram to make its forward stroke, only when the pusher and coke guide machines are aligned with the same oven of the battery.

According to a still further aspect of the invention, there is provided for a horizontal coke oven battery, coke discharging plant of the kind referred to, including a pipe line for and adjacent each oven of the battery and extending from the pusher to the coke side of the latter, a pressure fluid supply source carried by and travelling with the pusher machine or the coke guide machine, means for coupling the said supply source to one end of the pipe line of an oven with which the machine carrying the supply source is aligned, 45 50 55 and an electric switch normally preventing the

pusher machine ram from being driven forwardly but operable by the fluid pressure built up in the pipe line to which the said pressure fluid supply source is connected so as to render the said ram capable of making its forward stroke only when the pusher and coke guide machines are both aligned with the same oven.

From the foregoing, it will readily be understood that the invention provides an interlocking system between the pusher and coke guide machines in which the pusher ram is inoperable in its forward direction except when the said electric switch means in the circuit of the pusher ram operating means has been closed by the said pneumatically operated device—thus the pusher ram is normally inoperative in a forward direction and can only be rendered operative when the coke guide machine and the pusher machine have both been aligned with the same oven and the necessary connections have been made between the pipe line of the oven and the said fluid pressure supply source.

In one embodiment in accordance with the invention, and in which the pusher ram is electrically driven, the said means for normally rendering the pusher ram inoperative in a forward direction may comprise an electric switch adapted normally to interrupt the electric circuit of the electrical mechanism for effecting the forward stroke of the ram; the said pressure fluid supply source, which may be an air compressor, may be carried by the pusher machine, the supply source having means, e. g. a flexible hose, for coupling it to the pusher side end of the pipe line of an oven with which the pusher machine is aligned; the coke guide machine may carry a dead-end pipe (which may be furnished with a pressure relief valve) having means for coupling it to the adjacent end of the pipe line of an oven with which the coke guide machine is aligned; and the fluid pressure (e. g. pneumatically) operated device may be furnished between the compressor and the said flexible hose or like coupling means on the pusher machine, such fluid pressure operated device being associated with the said electric switch means so that, when operated by fluid pressure, it will cause the switch means to render the pusher ram operable in the forward direction, this operation of the switch only being effected when the pusher machine and the coke guide machine are aligned with one and the same oven, and the dead-end pipe of the coke guide machine is coupled to the same oven pipe line as the fluid pressure supply source on the pusher machine.

In another embodiment in accordance with the invention and in which the pusher ram is electrically driven, the said means for normally rendering the pusher ram inoperative in a forward direction may again comprise a self-opening electric switch means adapted normally to interrupt the electric circuit of the electrical mechanism for effecting the forward stroke of the pusher ram, and the said pressure fluid supply source, which again may, and preferably does, comprise an air compressor, may be mounted on the coke guide machine, such pressure fluid supply source being furnished with a flexible hose or other suitable coupling means by which it may be connected to the adjacent end of any one of the pipe lines of the ovens of the battery, and these pipe lines may each be provided at the pusher side of the battery with a fluid pressure (e. g. pneumatically) operated device adapted, when the pusher machine is aligned with the

oven with which such fluid pressure operated device is associated, to operate the said electric switch means to render the pusher ram operable in a forward direction.

5 The said fluid pressure operated devices may each comprise a cylinder furnished with a piston, the piston rod of which constitutes a push rod, such piston being ordinarily (i. e. when the piston is not subjected to fluid pressure) retained by 10 spring means in a position in which the said push rod is retracted, but the piston serving to project the push rod when the fluid pressure in the associated pipe line and cylinder is built up to an appropriate pressure by fluid (e. g. air) 15 received from the fluid pressure supply source on the coke guide machine.

The said plunger may be arranged to cooperate with a lever arrangement on the pusher machine for controlling the said electric switch 20 and adapted, when the pusher machine is aligned with the same oven as the coke guide machine and the said fluid pressure is built up in the pipe line of this oven, to close the electric switch to render the pusher ram operable in a forward direction, this forward movement of the ram being 25 independently initiated through a manual control.

It is preferred to arrange the said oven pipe lines (which extend from the pusher to the coke 30 side of the battery) below the ovens instead of above them, for, in the former position, the pipes are subjected to less intense heat conditions than would be the case if the pipe lines were arranged over the top of the battery.

35 If desired, the arrangement may also be such that the coupling of an oven pipe line to the pusher machine and the coke guide machine as above explained, may serve simultaneously to interrupt the traction circuits of the pusher and 40 coke guide machines so that they cannot long travel with respect to the battery.

In the first embodiment of the invention above referred to, a quick release valve may be provided in the dead-end pipe of the coke guide machine 45 for releasing the fluid pressure in an oven pipe line when it is desired to do so, for example, to enable a workman, in the case of an emergency, to stop the forward stroke of the ram at any 50 moment, or to open the pipe line to the atmosphere when the pushing operation has been completed. A similar release valve may be provided in the second embodiment of the invention above referred to.

If desired an electric indicator light may be 55 provided on the pusher machine or the coke guide machine or on both these machines and be arranged to indicate when the said quick release valve is opened.

Although, in the two embodiments of the invention referred to, the pressure fluid supply 60 source may be mounted on the coke guide machine and the pusher machine respectively, it should be understood that the arrangement may, in either case, be reversed so that the pressure 65 fluid supply source is on the opposite side of the battery from that above set out, the positions of the other parts of the interlocking system being readjusted to suit this reversal of the position of the fluid pressure supply source.

70 The interlocking system preferably only controls the forward motion of the pusher ram, the latter being capable of making its return stroke independently of the control exercised by the interlocking system.

75 In order that the nature of the invention and

the method of carrying it into practice may be more thoroughly understood, two embodiments of the same will now be described with reference to the accompanying drawings, in which:

Figure 1 is a diagrammatic part vertical cross-sectional elevation of a coke oven battery and diagrammatically shows the coke-discharging plant for such battery, this plant having the present invention applied thereto;

Figure 2 is a part horizontal sectional and top plan of the arrangement shown in Figure 1;

Figure 3 is a view similar to Figure 1 but shows another embodiment according to the invention;

Figure 4 is an enlarged part-horizontal sectional and top plan of a device for coupling together two parts of the pressure fluid conduit arrangement of the interlocking system of the plant according to the invention;

Figure 5 is an enlarged longitudinal sectional elevation of the fluid pressure operated device and its co-operating lever arrangement on the pusher machine employed in the embodiment of the invention shown in Figure 3; and

Figure 6 is a plan view of the contact plate of the said lever arrangement.

In the drawings, the coke oven battery is indicated by the reference 1 and the ovens of this battery by the reference 2. The longitudinal vertical pusher machine side face of the masonry of the battery is braced by longitudinally spaced vertical buckstays 3 whilst the opposite longitudinal side face of the masonry is braced by similar buckstays 4, the buckstays being arranged opposite the heating walls between the ovens of the battery in the usual manner and as is shown in Figure 2 of the drawings.

On one side of the battery, hereinafter called the "pusher side," a trackway 5 is provided upon which the pusher machine 6 is adapted to travel parallel to the battery. The pusher machine has a pusher ram 7 movable longitudinally at right angles to the longitudinal pusher side face of the battery for "pushing" the ovens of the battery in the usual manner.

A bench 8 is arranged along the pusher side of the battery between the pusher machine 6 and the battery.

On the side of the battery opposite to the pusher machine, and hereinafter referred to as the "coke side" of the battery, a further longitudinal bench 9 is provided and on this is carried a trackway 10 for the coke guide machine 11 which is adapted to travel along the coke side of the battery parallel to the latter. The coke guide machine is provided with a coke guide 12 and means for moving it longitudinally (at right angles to the adjacent longitudinal side face of the battery) with respect to the coke guide machine so as to introduce the guide into the end of an oven when the door has been removed from the latter.

The plant so far described may be of any usual or conventional design.

Figures 1 and 2 of the drawings show one arrangement of interlocking system according to this invention applied to the coke-discharging plant of the battery and, as will be seen, a pipe line 13 extends adjacent each oven, and at a level below the oven sole, from the pusher side to the coke side of the battery.

The coke side end of each pipe line 13 has an upwardly directed part 14 which extends to a level above the coke side bench 9 and above the level of the soles of the ovens, the part 14 of the pipe line being secured by cleats 15 to an adjacent

buckstay 4. The upper end of the part 14 of the pipe line is provided with one half 16 of a quick release coupling (which may be a self-sealing coupling), the other half 17 of which is carried by one end of a flexible hose 18 hereinafter more fully referred to.

The pusher side end of the pipe line 13 is carried under the side bench 8 and has an upward extension 19 supported, for example, by the stanchions 20 of a handrail and at its upper end this pipe line extension 19 is furnished with one half 21 of a quick release coupling (which may be a self-sealing coupling), the other half 22 of which is carried by the free end of a flexible hose 23 having its other end coupled to an air pressure gauge 24 and a pressure fluid operated device comprising a cylinder 25 (Fig. 2) in which is arranged a piston, not shown, adapted, when air pressure is built up in the interlocking system to a sufficient extent, to move in the said cylinder and so to cause the closing of an electric switch 66' in the electric circuit 72, 73 of the pusher ram motor controller for motor 36' (Fig. 3) so that the ram 7 may be operated to make its forward stroke, the said electric switch being spring loaded or otherwise suitably constructed for causing it normally to remain in the open position so that the pusher ram is normally inoperable in the forward direction and can only be rendered operable by the closing of the said switch (or an alternative switch which may be provided, if desired, to short circuit the said switch).

The switch 66' may be of a type having two leads 72 which connect with motor 36' and both of which connect with a single contact point. The purpose of this is to enable the pusher ram operator to operate the circuit to retract the ram 7 at will, such circuit not being influenced in any manner by the interlocking mechanism. For advancing the ram, however, connection must be made between the contact point for leads 72 and the third lead 73 to the motor 36', to connect the third lead 73 with one of the two leads 72, to complete the circuit 72, 73 for advancing the pusher ram 7 into the ovens. It is this circuit 72, 73 that is the subject of the interlock and under the control of the coke guide machine operator.

The construction of the cylinder 25 is similar to the construction of the cylinder 39 shown in Fig. 5.

The said position in the cylinder 25 is preferably arranged only to control the forward stroke of the ram and not the withdrawal of the latter.

An electric indicator light or lights may be provided on the pusher machine and/or the coke guide machine to indicate whether the piston is in the "ram energized" position or not.

On the pusher machine is mounted, in any suitable position, an air compressor 26 connected to a receiver 27 having its outlet connected to the cylinder 25 by a pipe 28 including a control cock 29, this cock enabling the supply of pressure fluid to the said cylinder 25 and the flexible hose 23 to be cut off or regulated as and when desired.

Until the flexible hose 23 is to be connected to a pipe line 13 of an oven, it is engaged in the bifurcated or hooked end of a supporting member which may be in the form of a lever 30 or equivalent member pivotally carried on the pusher machine and serving normally to maintain closed an electric switch 31 in the electrical circuit of the electrical traction means for traversing the pusher machine in the direction of

the length of the battery, the arrangement being, however, such that when the hose 23 is unhooked from the lever 30 to couple it to the coupling half 21 carried by the pipe line 13, the switch 31 will automatically open and break the said electric circuit so that further long travel of the pusher machine will be prevented until the hose 23 has again been disconnected from the pipe line 13 and re-hung upon the lever 30.

On the coke guide machine 11 is mounted a pipe 32, herein referred to as the "dead-end pipe," permanently connected at one end by a flexible hose 33 to a quick release valve 34 also carried by the coke guide machine. This valve normally closes its end of the dead-end pipe but can be opened quickly to release the pressure in the interlocking system when this is to be disconnected or in the case of emergencies. The other end of the dead-end pipe 32 is connected to the opposite end of the flexible hose 18 to that end carrying the quick release coupling part 17 previously described.

The hoses 18 and 23 are preferably of such a length that neither of them is capable of being connected to a pipe line 13 other than that of the oven 2 with which the pusher machine or coke guide machine carrying the hose is aligned.

A switch 35, similar to the hereinbefore described switch 31, may be provided on the coke guide machine for the purpose of interrupting, when the hose 18 is coupled to a pipe line 13, the supply of electrical energy to the electrical driving or traction means for effecting the long travel of the coke guide machine, the said switch 35 having a lever 36 or an equivalent member upon which the coupling end of the hose 18 may be hooked or engaged when the hose is not in use for connecting the dead-end pipe 32 to a pipe line 13, the hose serving to depress the lever 36 so as to close the switch 35 to close the electric circuit to the said electrical driving means, the said circuit being opened automatically when the hose is lifted from the lever 36 to couple it to the adjacent end of a pipe line 13.

Assuming that the pusher side and coke side doors 37 and 38 (diagrammatically illustrated in the drawings) of the same oven have been removed and that the pusher machine 6 and the coke guide machine 11 have been lined up in their respective positions for pushing the said oven, then the hose 23 on the pusher machine and the hose 18 on the coke guide machine are respectively coupled to the adjacent ends of the pipe line 13 of the oven with which the said machines are aligned. So connecting the hoses 23 and 18 to the pipe line releases the levers 30 and 36 respectively of the switches 31 and 35 and interrupts the traction circuits of the pusher and coke guide machines so that they cannot long travel.

The quick release valve 34 on the coke guide machine should, at this stage, be closed so that as soon as air is fed to the pipe line 13 of the interlocking system from the air compressor 26, which compressor 26 is now started and is, or if already in operation is, placed in communication with the pipe line 13 by, for example, the manipulation of an appropriate cock, such as the cock 29. Thus air pressure is built up in the pipe line and eventually the piston in the control cylinder 25 is actuated, whereupon the electric switch 66, previously rendering the pusher ram incapable of making its forward movement, is operated and the ram becomes operable in the

forward direction and the pushing operation may be commenced.

If it should so happen that the flexible hoses 18 and 23 respectively on the coke guide machine 11 and the pusher machine are not coupled to the same pipe line 13, air pressure cannot be built up in the pipe line and therefore the control piston in the control cylinder 25 will not operate and the ram controller will not be energized to enable the ram to make its forward stroke.

Assuming that the connections have been properly made, then should it be necessary to open the quick release valve 34 for one reason or another, the workman at the coke side of the battery can open the quick release valve 34 and so stop the forward stroke of the pusher ram.

If desired, an electric indicator light (not shown in the drawings) may be provided and arranged to be illuminated in the pusher machine when the release valve 34 is opened. This release valve 34 is also adapted to be used to open the interlocking system to the atmosphere at the completion of a "pushing" operation so that the hoses of the system may be disconnected from the oven pipe with safety.

After the disconnection of the hoses 18 and 23, these are re-hung upon the levers 36 and 30 respectively so that the switches 35 and 31 are closed and the coke guide and pusher machines 30 are again rendered capable of long travel.

Although flexible hoses 18 and 23 have been described above for connecting the coke guide machine and the pusher machine respectively to the opposite ends of a pipe line 13, any other suitable coupling means may be employed for this purpose, and, for example, coupling devices of the form hereinafter described may be employed instead of the hoses.

In this further embodiment, the compressor 26 is mounted on the coke guide machine 11 instead of on the pusher machine 6, and the dead-end pipe 32 of the first-mentioned embodiment of the invention is eliminated. Furthermore, a series of

50 fluid (e. g. air) pressure operated devices (generally indicated by the reference 39) is provided, and these are connected one to the pusher side end of each pipe line 13, the devices being carried by the structure of the bench 8 on the pusher side of the battery at a level somewhat below the bench 8. Thus each pipe line 13 is provided with an individual fluid pressure operated device 39.

Each pressure fluid operated device 39 comprises, as shown in Figure 5, a cylinder 40 connected at one end to a pipe line 13 and having a piston 41 sliding within it but urged inwardly, with respect to the cylinder, by a spring 42. The cylinders 40 are all arranged with their axes perpendicular to the pusher side vertical longitudinal face of the battery, and the piston of each cylinder has coaxially fixed to it a plunger rod 43 passing through the outer end of the cylinder 40 and furnished at its outer end with a bulbous or rounded head 44 or a roller or equivalent device.

The head 44, or the equivalent device, of the plunger rod 43 is adapted to cooperate with a contact plate 45 carried near its ends by the lower ends of the side links of a control lever

46 pivotally mounted at its upper end upon a pivot pin 47 supported by a drop bracket 48 on the battery side of the pusher machine 6. The said contact bar 45 is, as shown in plan in Figure 6, conveniently in the form of a rigid strip having its end portions curved away from the battery.

The lever 46 is urged into the vertical position shown in full lines in Figures 3 and 5 by one or more springs 49 carried upon a rod or rods 50 supported by the drop bracket 48 and furnished, or each furnished, with a pressure-adjusting nut 51.

The contact plate 45 is centrally provided with an abutment member 45' adapted, when the plate is swung by a plunger 43 away from the battery, to engage the plunger 65 of an electric switch 66 arranged in the electric circuit 72, 73, of the electrical driving mechanism 36' which effects the forward stroke of the pusher ram, the switch 66 normally being maintained open but being closed by the action of the plunger 43 on the contact plate 45.

The compressor 26, or its receiver 27 where provided, is adapted to be coupled to the coke side end of a pipe line 13 and this can either be effected by a flexible hose such as the hose 23 described with reference to Figures 1 and 2, or by an alternative form of coupling device shown in Figures 3 and 4 and subsequently described, or by any other suitable coupling means.

Assuming that the compressor 26 has been coupled to the coke side end of a pipe line 13 of an oven with which the coke guide machine is aligned, and assuming that the control valve 29' has been operated to place the pipe line in communication with the compressor, then fluid pressure will be built up in the pipe line 13 and in the cylinder 48 of the corresponding fluid pressure operated device 39. Thus the plunger 43 of this device 39 will be projected and, if the pusher machine 6 has been aligned with the same oven 2 as the coke guide machine, the plunger will engage the contact plate 45 of the control lever 46 on the pusher machine and will cause this lever to swing upon its pivot away from the battery and so to close the electric switch 66, thereby rendering the pusher ram operative in a forward direction so that the pushing operation can be initiated.

Should it be that when the plunger rod 43 is projected from its cylinder the pusher machine is not yet aligned with the oven with which the coke guide machine is aligned but is in the process of being so aligned, then the ram of the pusher machine will not become forwardly operable until the pusher machine has been moved along its trackway into alignment with the oven in question and, in being so moved, has had its control arm 46 operated by the head 44 of the projected plunger rod 43 riding along one of the curved ends of the contact plate 45 of the lever 46 and so forcing this lever outwards away from the battery to close the pusher ram controlling switch 66.

The flexible hose coupling devices previously described herein are coupled to the pipe lines manually and, as has previously been stated, may be replaced by alternative coupling devices which may be manually operated or automatically operated. Thus, for example, an alternative form of manually operated coupling may comprise a pipe connection having a flared rubber nozzle on a universal joint and adapted to be thrown over by hand.

An automatic coupling arrangement is shown in Figures 3 and 4. In this arrangement, the upper end of the upwardly extending part 14 of the pipe line 13 is furnished with an elbow 54 passing into and secured in a horizontally extending passage or port in the outer flange 55 of the associated buckstay 4, the open end of the pipe 14 at the coke side of the battery thus being horizontally directed and disposed in a vertical plane and preferably flush with the outer flange 55 of the buckstay.

The coupling comprises a tube 56 arranged on the coke guide machine horizontally and at right angles to the longitudinal face of the coke oven battery, the tube 56 being fixed in a bracket 57 on the coke guide 12 and arranged to move with this guide to and from the coke oven battery, the said tube also being slidably carried by a bracket 58 on the frame 59 of the coke guide machine. The tube 56 is coupled by a flexible hose 60 to the air compressor 26 or to an intermediate receiver 27.

The battery end of the tube 56 is provided with a metal sealing cup 61 containing a resilient, e. g. soft rubber, cup washer 62 or an equivalent member supported on the inside by a further metal cup 63, the resilient washer 62 projecting beyond the battery edges of the metal cups 61 and 63 so that its free edge may seat resiliently upon the portion of the buckstay flange 55 surrounding the end of the oven pipe line 13 to which the said tube is to be coupled.

Normally the said cup washer will be held clear of the battery of the buckstays 4, but when the coke guide machine has been aligned with an oven of the battery and the coke guide 12 is moved up into the mouth of the oven, the resilient cup washer 62 will automatically be moved up to the buckstay flange 55 so as to make a fluid-tight joint herewith and so place the compressor 26 and the pipe line 13 in sealed communication. A strong compression spring 64 may be provided on the tube 56 and be arranged so that it will assist in the withdrawal of the cup washer 62 from the battery when the coke guide 12 is withdrawn from the oven, and the said tube may be capable of resilient axial movement independently of the coke guide so as to compensate for any inequalities in the condition of the various buckstays with which the cup washer has to engage.

The valve 29' between the receiver 27 and the flexible hose 60 may be a three-way valve so that the compressor may be placed in connection with the hose 60, or this connection may be interrupted and the compressor opened to the atmosphere or put into service for some other purpose.

Cup washer type coupling devices such as described with reference to Figures 3 and 4 may be employed in place of the flexible hoses 18 and 23 in the interlocking system described with reference to Figures 1 and 2.

The fluid pressure supply source, e. g. the compressor 26, may be a part of the normal equipment of coke oven discharging plant and may, when on the pusher machine, for example, be part of the decarbonizing system on the pusher machine.

The invention as hereinabove set forth is embodied in particular form and manner but may be variously embodied within the scope of the claims hereinafter made.

I claim:

1. Horizontal coke oven battery coke-discharging apparatus comprising, a pusher machine and a coke guide machine movable from oven to oven

11

along opposite sides of a battery of horizontal coke ovens, with a ram mounted on said pusher machine, electric switch means on the pusher machine normally rendering inoperative electric driving gear for effecting the forward pushing stroke of the pusher machine ram, fluid pressure operated means adapted to operate said electric switch means to enable the pusher ram to make its forward stroke, fluid pressure lines individualized to the respective ovens, a source of fluid pressure for supplying fluid under pressure to the fluid pressure lines, to energize the fluid pressure operated means to operate the electric switch, means to connect the source of fluid pressure individually with the individual fluid pressure lines, and means for impressing the pressure of the fluid of the individual lines onto the fluid pressure operated means that is to operate said electric switch means; and in which the source of fluid under pressure, and the means to connect the same individually with the individual fluid pressure lines, are carried by, for travel from oven to oven with, one of said machines, and the means for impressing the pressure of the fluid of the individual lines onto the fluid pressure operated means that operates the electric switch means, is carried by, for travel from oven to oven with, the other of said machines, and in which the means to connect the source of fluid under pressure with the individual fluid pressure lines and the means for impressing the fluid pressure, are such that they individually can be operatively connected to only the pipe line of one oven at a time, and are necessarily individually operatively disconnected from the individual pipe lines whenever the machines carrying them are individually out of alignment with the ovens associated with the respective pipe lines, whereby to permit pushing of any of the ovens only when both the coke guide machine and pusher machine are aligned with one and the same oven of the battery, and to prevent accidental pushing of any of the ovens whenever one machine is aligned with any one of the ovens but the other is not simultaneously also in alignment therewith for the coke pushing operation of said oven.

2. Horizontal coke oven battery coke-discharging apparatus comprising, a pusher machine and a coke guide machine movable from oven to oven along opposite sides of a battery of horizontal coke ovens, with a ram mounted on the pusher machine, an electrical switch on the pusher machine for normally preventing its pusher ram from being driven forwardly in pushing, actuating means on the pusher machine for actuating the electric switch to render the ram capable of partaking of its forward pushing stroke, a pipe line for, and individualized to, each oven of a battery and extending from the pusher side to the coke side of the battery, a pressure fluid supply source for said pipe lines carried by, and traveling from oven to oven with, said coke guide machine, and means on the coke guide machine and movable from oven to oven therewith, for impressing the pressure of fluid pressure from said pressure fluid supply source on the coke guide machine individually in each pipe line, and in which an element movable under pressure of fluid pressure in a pipe line is carried by, for movement from oven to oven with, the pusher machine and in position on the pusher machine to impress the pressure of fluid pressure in a pipe line onto the actuating means on the pusher machine for actuating the electrical switch to render the ram capable of partaking of its forward pushing stroke, only when the pusher ma-

chine, on which said element is carried is otherwise aligned with the oven associated with a pipe line for the pushing operation of that oven, and in which a pneumatically operated device is provided for each pipe line on the pusher side of the battery, which devices are maintained in fixed relation to the battery and are operable to a position, by pneumatic pressure of air built up in their pipe lines, to engage and thereby transmit the pressure of air in their lines onto said element

10 movable under pressure of a pipe line and carried on the pusher machine to impress the pressure of a pipe line onto the actuating means on the pusher machine for actuating the electrical switch for pushing of the pusher ram.

3. In horizontal coke oven battery coke discharging apparatus, the combination with a pusher machine and a coke guide machine movable from oven to oven along opposite sides of

20 a battery of horizontal coke ovens; a ram mounted on said pusher machine; pusher ram control means on the pusher machine for normally rendering the pusher ram inoperable in a forward direction; pressure operated means on said pusher

25 machine adapted to be actuated by impression of pressure from a pressure fluid supply source and arranged to operate said pusher ram control means, to render the ram operable in a forward direction, when the pressure operated means

30 is so actuated; and a pipe line for and individual to each oven of the battery and extending from the pusher side to the coke side of the battery; of a pressure fluid supply source carried by and traveling from oven to oven with, one of said

35 machines; coupling means on, and movable from oven to oven with, said machine carrying the pressure fluid supply source, for temporarily coupling said pressure fluid supply source on said machine to only one of said pipe lines at a time

40 and being such that the coupling of the pressure fluid supply source on said machine to a pipe line can only be effected from said machine, and then only when said machine is aligned with the oven associated with that pipe line; and fluid pressure impressing means on and carried by, and traveling from oven to oven with, the other

45 of said machines for operable connection with only one of said pipe lines at a time, and likewise arranged so that its operative connection to a pipe line can only be effected from the machine carrying it, and then only when the machine carrying it is aligned with the particular oven associated with that pipe line, for impressing the pressure of fluid in the line onto the pressure op-

50 erated means for the pusher arm control means only when the two said machines are aligned respectively with the opposite ends of one and the same oven, said coupling means and said fluid pressure impressing means being necessarily dis-

55 connected from the pipe lines when the machines carrying them are out of alignment with the ovens associated with the respective pipe lines, thus preventing impressing of pressure by the individual lines onto the pressure operated means for the pusher ram control means whenever both of said

60 machines are not aligned with one and the same oven for pushing the same.

4. Horizontal coke oven battery coke discharging apparatus comprising the combination with a pusher machine and a coke guide machine movable from oven to oven along opposite sides of a battery of horizontal coke ovens; a ram mounted on said pusher machine; pusher ram control means on the pusher machine for normally rendering the pusher ram inoperable in a forward di-

rection; pressure operated means on said pusher machine adapted to be actuated by impression of pressure from a pressure fluid supply source and arranged to operate said pusher ram control means, to render the ram operable in a forward direction when the pressure operated means is so actuated; and a pipe line for and individual to each oven of the battery and extending from the pusher side to the coke side of the battery; of a pressure fluid supply source carried by, and traveling from oven to oven with, one of said machines; coupling means on, and movable from oven to oven with, said machine carrying the pressure fluid supply source, for temporarily coupling the said pressure fluid supply source on said machine to only one of said pipe lines at a time and being such that the coupling of the pressure fluid supply source on said machine to a pipe line can only be effected from said machine, and then only when said machine is aligned with the oven associated with that pipe line; and fluid pressure impressing means on and carried by, and traveling from oven to oven with, the other of said machines for operable connection with only one of said pipe lines at a time, and likewise arranged so that its operative connection to a pipe line can only be effected from the machine carrying it, and then only when the machine carrying it is aligned with the particular oven associated with that pipe line, for impressing the pressure of fluid in the line onto the pressure operated means for the pusher ram control means only when the two said machines are aligned respectively with the opposite ends of one and the same oven, said coupling means and said fluid pressure impressing means being necessarily disconnected from the pipe lines when the machines carrying them are out of alignment with the ovens associated with the respective pipe lines, thus preventing impressing of pressure by the individual lines onto the pressure operated means for the pusher ram control means whenever both of said machines are not aligned with one and the same oven for pushing the same, and in which the pressure fluid supply source is carried by the pusher machine, and comprises an air compressor, and in which the fluid pressure impressing means is carried by the coke guide machine and comprises a dead-end pipe, and in which the pressure operated means on the pusher machine for operating the pusher ram control comprises a pneumatically operable device so included in the pneumatic system that when sufficient air pressure builds up in a pipe connected therewith, it will be pneumatically actuated thereby to render the pusher ram operable in a forward direction.

5. Coke discharging apparatus as claimed in claim 4, and wherein a flexible hose is provided for connecting the said dead-end pipe, individually, as required, to its end of each of the said pipe lines.

6. Coke discharging apparatus as claimed in claim 5, and wherein the flexible hose is of a length sufficient to couple it solely to a pipe line of a single one of the ovens, and then only when the coke guide is in pushing alignment with the oven associated with that pipe line.

7. Coke discharging apparatus as claimed in claim 4, and wherein the dead-end pipe comprises a self-sealing coupling member, individually attachable in gas tight relation over a port of each of said pipe lines.

8. Horizontal coke oven battery coke discharging apparatus comprising the combination with a

pusher machine and a coke guide machine movable from oven to oven along opposite sides of a battery of horizontal coke ovens; a ram mounted on said pusher machine; pusher ram control means on the pusher machine for normally rendering the pusher ram inoperable in a forward direction; pressure operated means on said pusher machine adapted to be actuated by impression of pressure from a pressure fluid supply source and arranged to operate said pusher ram control means, to render the ram operable in a forward direction when the pressure operated means is so actuated; and a pipe line for and individual to each oven of the battery and extending from the pusher side to the coke side of the battery; of a pressure fluid supply source carried by, and traveling from oven to oven with, one of said machines; coupling means on, and movable from oven to oven with, said machine carrying the pressure fluid supply source, for temporarily coupling the said pressure fluid supply source on said machine to only one of said pipe lines at a time and being such that the coupling of the pressure fluid supply source on said machine to a pipe line can only be effected from said machine, and then only when said machine is aligned with the oven associated with that pipe line; and fluid pressure impressing means on and carried by, and traveling from oven to oven with, the other of said machines for operable connection with only one of said pipe lines at a time, and likewise arranged so that its operative connection to a pipe line can only be effected from the machine carrying it, and then only when the machine carrying it is aligned with the particular oven associated with that pipe line, for impressing the pressure of fluid in the line onto the pressure operated means for the pusher ram control means only when the two said machines are aligned respectively with the opposite ends of one and the same oven, said coupling means and said fluid pressure impressing means being necessarily disconnected from the pipe lines when the machines carrying them are out of alignment with the ovens associated with the respective pipe lines, thus preventing impressing of pressure by the individual lines onto the pressure operated means for the pusher ram control means whenever both of said machines are not aligned with one and the same oven for pushing the same, and in which the pressure fluid supply source is carried by the coke guide machine and comprises an air compressor, and in which the fluid pressure impressing means is carried by the pusher machine and comprises an element movable under the pressure of pressure fluid in a pipe line, to impress the pressure of the pressure fluid in the pipe line onto the pressure operated means on the pusher machine for operating the pusher ram control thereon, and in which a pneumatically operated device is provided in fixed relation to the oven battery for each pipe line on the pusher side of the battery, which device is operable to a position, by pneumatic pressure of air built up by the compressor in the pipe line, to engage and thereby transmit the pressure of air in its line onto the element on the pusher machine that is movable to impress the pressure onto the pressure operated means to operate the pusher ram control means.

9. Coke discharging apparatus as claimed in claim 6, and wherein a flexible hose is provided for connecting the said air compressor, individually, as required, to its end of each of the said pipe lines.

10. Coke oven discharge apparatus as claimed in claim 7, and wherein the flexible hose is of a length sufficient to couple it solely to a pipe line of a single one of the ovens, and then only when the coke guide is in pushing alignment with the oven associated with that pipe line.

11. Horizontal coke oven battery coke discharging apparatus comprising the combination with a pusher machine and a coke guide machine movable from oven to oven along opposite sides of a battery of horizontal coke ovens; a ram mounted on said pusher machine; pusher ram control means on the pusher machine for normally rendering the pusher ram inoperable in a forward direction; pressure operated means on said pusher machine adapted to be actuated by impression of pressure from a pressure fluid supply source and arranged to operate said pusher ram control means, to render the ram operable in a forward direction when the pressure operated means is so actuated; and a pipe line for and individual to each oven of the battery and extending from the pusher side to the coke side of the battery; of a pressure fluid supply source carried by, and traveling from oven to oven with, one of said machines; coupling means on, and movable from oven to oven with, said machine carrying the pressure fluid supply source, for temporarily coupling the said pressure fluid supply source on said machine to only one of said pipe lines at a time and being such that the coupling of the pressure fluid supply source on said machine to a pipe line can only be effected from said machine, and then only when said machine is aligned with the oven associated with that pipe line; and fluid pressure impressing means on and carried by, and traveling from oven to oven with, the other of said machines for operable connection with only one of said pipe lines at a time, and likewise arranged so that its operative connection to a pipe line can only be effected from the machine carrying it, and then only when the machine carrying it is aligned with the particular oven associated with that pipe line, for impressing the pressure of fluid in the line onto the pressure operated means for the pusher ram control means only when the two said machines are aligned respectively with the opposite ends of one and the same oven, said coupling means and said fluid pressure impressing means being necessarily disconnected from the pipe lines when the machines carrying them are out of alignment with the ovens associated with the respective pipe lines, thus preventing impressing of pressure by the individual lines onto the pressure operated means for the pusher ram control means whenever both of said machines are not aligned with one and the same oven for pushing the same, and in which at least one of the two units consisting of the coupling means and the fluid pressure impressing means comprises a self-sealing coupling member in the form of a cup fixed upon a tube carried by a movable structure on the machine carrying the cup member, for mechanical movement into individual connecting relationship with a port of the pipe line of the individual ovens when the machine carrying the cup member is in pushing alignment with the respective ovens.

12. Horizontal coke oven battery coke discharging apparatus comprising the combination with a pusher machine and a coke guide machine movable from oven to oven along opposite sides of a battery of horizontal coke ovens; a ram mounted on said pusher machine; pusher ram control

means on the pusher machine for normally rendering the pusher ram inoperable in a forward direction; pressure operated means on said pusher machine adapted to be actuated by impression of pressure from a pressure fluid supply source and arranged to operate said pusher ram control means, to render the ram operable in a forward direction when the pressure operated means is so actuated; and a pipe line for and individual to each oven of the battery and extending from the pusher side to the coke side of the battery; of a pressure fluid supply source carried by, and traveling from oven to oven with, one of said machines; coupling means on, and movable from oven to oven with, said machine carrying the pressure fluid supply source, for temporarily coupling the said pressure fluid supply source on said machine to only one of said pipe lines at a time and being such that the coupling of the pressure fluid supply source on said machine to a pipe line can only be effected from said machine, and then only when said machine is aligned with the oven associated with that pipe line; and fluid pressure impressing means on and carried by, and traveling from oven to oven with, the other of said machines for operable connection with only one of said pipe lines at a time, and likewise arranged so that its operative connection to a pipe line can only be effected from the machine carrying it, and then only when the machine carrying it is aligned with the particular oven associated with that pipe line, for impressing the pressure of fluid in the line onto the pressure operated means for the pusher ram control means only when the two said machines are aligned respectively with the opposite ends of one and the same oven, said coupling means and said fluid pressure impressing means being necessarily disconnected from the pipe lines when the machines carrying them are out of alignment with the ovens associated with the respective pipe lines, thus preventing impressing of pressure by the individual lines onto the pressure operated means for the pusher ram control means whenever both of said machines are not aligned with one and the same oven for pushing the same, wherein long travel means are provided, for travel from oven to oven with at least one of said machines, said long travel means including a replacement element requiring its placement in the long travel means for movement of said machine from oven to oven, and wherein each of the pressure fluid circuits for the individual ovens, comprises an element requiring the replacement element of the long travel means for completion of the respective circuits, whereby to render temporarily inoperative the movement of the machine provided with long travel means, by its long travel means when a pressure fluid line is completed by the pressure of said replacement element in its pressure fluid circuit.

13. Horizontal coke oven battery coke-discharging apparatus comprising: the combination with a pusher machine and a coke guide machine movable from oven to oven along opposite sides of a battery of horizontal coke ovens, with a ram mounted on the pusher machine, an electric switch on the pusher machine for normally preventing its pusher ram from being driven forwardly in pushing, actuating means on the pusher machine and operable by fluid pressure, for actuating the electric switch to render the ram capable of making its forward pushing stroke, and a separate and independent pipe line for and adjacent each oven of a battery and extending from the pusher side to the choke side of the latter; of a pressure fluid supply source carried by, for travel from oven to oven with, one

of said machines, means carried by, for travel from oven to oven with, the machine on which the pressure fluid supply source is carried, for coupling the pressure fluid supply source temporarily to only one of said separate and independent pipe lines at a time, and then only when the machine carrying the pressure fluid supply source and its coupling, is otherwise aligned with the oven associated with that pipe line for the pushing operation of that oven, and means for impressing pressure of said lines onto said actuating means, for actuating the electric switch for the ram, said means being carried by, for travel from oven to oven with, the other of said machines, and being operable for operative connection with only one of said pipe lines at a time, and then only when the machine carrying it is otherwise aligned with the oven associated with that pipe line for the pushing operation of that oven, said means for coupling on one of said machines, and said means for impressing pressure on the other of said machines, being such that they are necessarily individually operatively disconnected from the individual pipe lines, whenever the machines carrying them are individually out of pushing alignment with the ovens associated with respective pipe lines, whereby to prevent accidental pushing of any oven whenever one of said machines is aligned but the other is not simultaneously also in pushing alignment with one and the same oven.

14. Horizontal coke oven battery coke-discharging apparatus comprising: the combination with a pusher machine and a coke guide machine movable from oven to oven along opposite sides of a battery of horizontal coke ovens, with a ram mounted on the pusher machine, an electric switch on the pusher machine for normally preventing its pusher ram from being driven forwardly in pushing, actuating means on the pusher machine and operable by fluid pressure, for actuating the electric switch to render the ram capable of making its forward pushing stroke, and a separate and independent pipe line for and adjacent each oven of a battery and extending from the pusher side to the coke side of the latter; of

a pressure fluid supply source carried by, for travel from oven to oven with, one of said machines, means carried by, for travel from oven to oven with, the machine on which the pressure fluid supply source is carried, for coupling the pressure fluid supply source temporarily to only one of said separate and independent pipe lines at a time, and then only when the machine carrying the pressure fluid supply source and its coupling, is otherwise aligned with the oven associated with that pipe line for the pushing operation of that oven, and means for impressing pressure of said lines onto said actuating means, for actuating the electric switch for the ram, said means being carried by, for travel from oven to oven with, the other of said machines, and being operable for operative connection with only one of said pipe lines at a time, and then only when the machine carrying it is otherwise aligned with the oven associated with that pipe line for the pushing operation of that oven, said means for coupling on one of said machines, and said means for impressing pressure on the other of said machines, being such that they are necessarily individually operatively disconnected from the individual pipe lines, whenever the machines carrying them are individually out of pushing alignment with the ovens associated with respective pipe lines, whereby to prevent accidental pushing of any oven whenever one of said machines is aligned but the other is not simultaneously also in pushing alignment with one and the same oven.
